(57) CLAIM

The ornamental design for an electronic device with lateral-openable display, as shown and described.

DESCRIPTION

FIG. 1 is a perspective view of an electronic device with lateral-openable display showing our new design with the display closed;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the electronic device with lateral-openable display of FIGS. 1-7 shown in an alternate position with the display open;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of the electronic device with lateral-openable display of FIGS. 1-7 shown in another alternate position with the display opened laterally;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

The dashed broken lines illustrate portions of the electronic device with lateral-openable display and form no part of the claimed design.

1 Claim, 12 Drawing Sheets
